UNITED STATES PATENT OFFICE

VICTOR R. DESPARD, OF SYRACUSE, NEW YORK, ASSIGNOR TO PASS & SEYMOUR, INC.
OF SYRACUSE, NEW YORK, A CORPORATION OF NEW YORK

DESIGN FOR AN ELECTRIC PILOT LIGHT FIXTURE

Application filed January 28, 1933. Serial No. 47,031. Term of patent 14 years.

To whom it may concern:

Be it known that I, VICTOR R. DESPARD, a citizen of the United States, and resident of Syracuse, county of Onondaga, and State of New York, have invented a new, original, and ornamental Design for an Electric Pilot Light Fixture, of which the following is a specification, reference being had to the accompanying drawing, forming a part thereof and in which:

Figure 1 is a perspective view of an elec-

tric pilot light fixture embodying the present design;

Figure 2 is a side elevation thereof;

Figure 3 is an end elevation thereof;

Figure 4 is a front view thereof; and

Figure 5 is a rear view thereof.

I claim as my invention:

The ornamental design for an electric pilot light fixture substantially as shown.

VICTOR R. DESPARD.
